United States Patent Office

Des. 185,551
Patented June 23, 1959

185,551

BOTTLE CARRIER

Clare E. Hodgman, Mamaroneck, N.Y., assignor to The Coca-Cola Company, Atlanta, Ga., a corporation of Delaware

Application December 1, 1958, Serial No. 53,585

Term of patent 14 years

(Cl. D58—5)

The drawing is shaded to indicate contrast in color.

I claim:

The ornamental design for a bottle carrier, as shown and as described.
